(57) **CLAIM**

The ornamental design for an insert for battery carrying tray as shown and described.

DESCRIPTION

FIG. 1 is a front, top, and left side perspective view of an insert for battery carrying tray, showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in FIGS. 1-7 depict portions of the insert for battery carrying tray that form no part of the claimed design.
